E. Q. Smith,

Mortising Machine.

Nov 13, 184.

Patented July 3, 1855.

UNITED STATES PATENT OFFICE.

EDWARD Q. SMITH, OF CINCINNATI, OHIO.

METHOD OF CUTTING STRAIGHT OR CURVED MORTISES.

Specification forming part of Letters Patent No. 13,184, dated July 3, 1855.

To all whom it may concern:

Be it known that I, EDWARD Q. SMITH, of the city of Cincinnati, in the county of Hamilton and State of Ohio, have invented a new and useful Improvement in Mortising-Machines for Mortising Straight and Curved Mortises; and I do hereby declare that the following is a full and exact description thereof, reference being had to the accompanying drawings forming part of this specification, and to the letters and figures of reference marked thereon, similar letters and figures referring to corresponding parts of the machine.

The nature of my improvement consists in the employment of two segment-pieces attached to the frame that carries the chisel, which segments are made to slide through guides, and when placed at an angle to each other and set in motion the said segments cause the mandrel to which the chisel is attached to make a curved movement, producing a curved mortise when put into operation, and when the said segments are placed in a right line with each other the movement of the mandrel is in a right line, and therefore makes a straight mortise.

I am aware of other machines previously made for making curved mortises, but none that would make a straight and curved mortise with the same machine and chisel, all that is required being a slight adjustment of parts to change it from a straight to a curved mortising movement.

To enable others skilled in the art to make and use my improvement, I will proceed to describe its construction and operation by referring to the accompanying drawings, of which—

Figure 1 represents a top view of the machine. Fig. 2 is a front elevation of the same, showing portions in section. Fig. 3 is a separate and front view of the machinery for carrying the mandrel that contains the mortising-chisel. Fig. 4 is a longitudinal sectional elevation of the portion of the machine represented in Fig. 3. Fig. 5 represents a sample of the work done by a machine in operation, showing one straight and two curved mortises.

The following is that portion of the specification referring directly to the drawings.

a a represent the general frame-work of the machine.

B B is a table worked on slides 9 9 and moved by the lever 10 and dovetailed piece 17. The table is provided with a clamp apparatus 15 for holding the piece being mortised.

c is the main driving-shaft of the machine, provided with pulleys *d* and *f*. The former drives the chisel-spindle *k* by means of the band 13 and pulley 16, and the latter or pulley *f* on shaft *c* drives the counter-shaft *g* by means of the belt 14, which shaft works the pitman *i*, that gives lateral motion to the frame *J* and *n n*, that carries the spindle *K* and chisel 18. The shaft *g* is provided with a nest of pulleys *h* and a sliding bar *m* across the face-plate on the end of the shaft *g*, for the purpose of adjusting different lengths of mortises. The pitman *i* is attached to the under part of the frame *J*, as represented in Fig. 4 at 20. The frame works on pivots *o* and *P* in order to give it the required lateral movements.

11 is the plate to which the frame-work *J* is attached.

6 6 represent the two segment-pieces for giving the curve to the mortise, the two ends of which pieces are attached to the frame *n n* by means of the thumb-screw 21, the said frame being provided with a slot 22 in order to elevate and lower the segment-pieces 6 6. The outside ends of said segment-pieces work in guides 12 12, which guides are made stationary with the exception of revolving or turning up and down.

In order to make a curved mortise, as represented by 6 in Fig. 5, the segment-pieces are to be placed at an angle somewhat near, as represented in Figs. 2 and 3, and when the reverse is required in the curve of a mortise, as represented at 8 in Fig. 5, the segments are to be placed in the reverse position, as denoted by the dotted lines 8 in Fig. 3. When a straight mortise is required, as represented at 7 in Fig. 5, the segments are placed in a right line, as represented by the dotted lines 7 in Fig. 3.

As before stated, the pitman *i*, together with the machinery to which it is attached, is used for giving the mandrel *K* and chisel 18 their lateral motion, and the mandrel and chisel receive their rotary motion by means of the belt 13.

The machine is used for mortising chair

stuff, and is capable of making any mortise required in the chair business of any size or curve, but can be used for all other purposes where mortises are required of the form represented in the sample figure of the accompanying drawings.

What I claim as my improvement, and desire to secure by Letters Patent, is—

The two segment-pieces 6 6, placed at an angle to each other or straight, so as to direct

the lateral movement of the mortising-chisel in a curved or right line, and thereby form a curved or straight mortise, as mentioned in the foregoing specification, all substantially for the purposes set forth.

EDWARD Q. SMITH.
